(57) **CLAIM**

The ornamental design for a nailer, as shown and described.

DESCRIPTION

FIG. 1 is a back view of the nailer.

FIG. 2 is a bottom view of the nailer.

FIG. 3 is a front view of the nailer.

FIG. 4 is a perspective view from the top and right side of the nailer.

FIG. 5 is a right side view of the nailer.

FIG. 6 is a left side view of the nailer; and,

FIG. 7 is an upper view of the nailer.

In each of FIGS. 1-7, broken lines illustrate portions of the nailer that form no part of the design.

1 Claim, 2 Drawing Sheets
